UNITED STATES PATENT OFFICE.

WILLIAM DUGUID, OF SEATTLE, WASHINGTON.

DESIGN FOR A CANOPY-COVER FRAME.

SPECIFICATION forming part of Design No. 33,235, dated September 18, 1900.

Application filed July 5, 1900. Serial No. 22,645. Term of patent 7 years.

To all whom it may concern:

Be it known that I, WILLIAM DUGUID, a citizen of the United States, residing at Seattle, in the county of King and State of Washington, have invented and produced a certain new and original Design for a Canopy-Cover Frame; and I do declare the following to be a full, clear, and exact description of the invention, such as will enable others skilled in the art to which it appertains to make and use the same.

My invention relates to a design for a new and useful article of manufacture—a canopy-cover frame.

5 The invention consists of the features hereinafter described and claimed, and is shown in the accompanying drawings, in which—

Figure 1 is a top plan view of a canopy-cover frame embodying my invention. Fig. 2 is an end elevation thereof.

5 The design embodies an oblong rectangular frame of peculiar shape and formation, said frame comprising a pair of spaced side rods 1, extending longitudinally in parallel relation. Between these rods 1 at intervals extend two series of transverse rods 2 and 3, of less length than the said rods 1. The rods 2 project in a horizontal plane between the rods 1 and are formed with intermediate up-

wardly-projecting inverted-U-shaped bails 4, 30 rising above the plane of the rods 1. The rods 3 extend diagonally from each rod 1 to the upper closed ends of the bails 4 and are formed with spiral loops 6, which encircle the rods 1. Each pair of rods 2 and 3 thus co-operate to form one of a series of transverse members having triangularly-shaped ends and an intermediate looped central portion, 40 said central portion being formed by the bail 4 and being closed at top and open at bottom, thus imparting a peculiar and distinctive appearance to the frame. Adjacent to each transverse member at each side of the frame 45 are parts 7 of hook form, which hang pendent from the rods 1.

Having thus described my invention, what I claim as new is—

The design for a canopy-cover frame, substantially as herein shown and described.

In testimony whereof I have hereunto set my hand in presence of two subscribing witnesses.

WILLIAM DUGUID.
